COAT

Jesse Block, New York, N. Y.

Application December 30, 1949, Serial No. 6,929

Term of patent 3½ years

(Cl. D3—4)

To all whom it may concern:

Be it known that I, Jesse Block, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my design.

Fig. 2 is the rear view of the coat shown in Fig. 1, and

Fig. 3 is another rear view of the coat shown in Figs. 1 and 2, illustrating the gathering of the waist line in loosened position.

I claim:

The ornamental design for a coat, substantially as shown.

JESSE BLOCK.
